AMOS CALLESON, OF BROOKLYN, NEW YORK, ASSIGNOR TO ADRIANCE MACHINE WORKS, INC., OF BROOKLYN, NEW YORK, A CORPORATION OF NEW YORK.

BOTTLE FILLING AND SEALING MACHINE

1,365,454.

Specification of Letters Patent. Patented Jan. 11, 1921.

Original application filed March 30, 1916, Serial No. 87,805. Divided and this application filed May 22, 1917. Serial No. 170,188.

To all whom it may concern:

Be it known that I, AMOS CALLESON, a citizen of the United States, residing at Brooklyn, in the county of Kings and State 5 of New York, have invented certain new and useful Improvements in Bottle Filling and Sealing Machines, of which the following is a specification.

This application constitutes a division of 10 my application for patent for a bottle filling and sealing machine filed March 30, 1916, Serial No. 87,805, on which application patent numbered 1,252,881 was granted Jan. 8, 1918, and it consists in that part of the improvements 15 embraced in such machine which have to do with operations on the closures to bring them into position over and then attach them to the bottle heads. In this specification I shall describe with detail the construction and operation of the parts with 20 which this application is directly concerned, as aforesaid, but treat the other parts in a more or less general way excepting in so far as a detailed description thereof may be required 25 in order to afford a clear understanding of the subject matter immediately in hand.

Referring to the accompanying drawings, 30 Figure 1 is a side elevation of the machine;

Fig. 2 is a horizontal sectional view approximately on the line 2—2 of Fig. 5;

Fig. 3 is a front elevation of the upper part of the machine;

Fig. 4 is a detail of the closure dispensing means;

Fig. 5 is a front-to-rear vertical sectional view, in the plane of the filling and sealing means, of the upper part of the machine;

Fig. 6 is a sectional view on line 6—6, Fig. 5;

Figs. 7, 8 and 9 are a front elevation, a side elevation and a horizontal sectional view of the delivery portion of the closure dispensing means, Fig. 8 being partly in section;

Figs. 10 and 11 show in plan (partly in section) and in side elevation certain parts appearing in Fig. 7; and

Figs. 12 and 13 are enlarged views of the compensating slide and plunger, respectively, in vertical section.

The frame of the machine includes a ped-

estal *a* and a housing *b* surmounting the same. At the front of the pedestal there is 55 a structure *c* for supporting the bottles while being filled and sealed. A front-to-rear extending suitably driven main shaft *d* is journaled in the housing and drives, through worm-gearing *e f* and a clutch means *f'* 60 (Fig. 2), a transverse horizontal shaft *g* (Fig. 5) having cams *h* thereon whereby is rocked a two-armed lever *i* fulcrumed on a shaft *j*, journaled in the housing parallel with shaft *g*, rolls *k* on said lever bearing 65 against the cams.

A vertically extending longitudinally channeled casting *l* is fixed to the front of the housing *b*, having spaced inwardly projecting plates *l'* at the front thereof and 70 thus forming a guide. Also secured to the housing *b* and partly closing this guide is a casting *m* upon which rests the base of the closure supply hopper *n*. In the aforesaid guide is movable what I shall hereinafter 75 term the "carrier" or "main slide" comprising a block *o*, vertically channeled at the front, and a front plate *p* secured to the block and formed with an opening *p'* and above the opening with a pair of spaced ears 80 *p*² (Figs. 2, 3 and 5). The main slide is reciprocated by the lever *i*, whose forward end is forked and suitably engaged in recesses (not shown) in the slide. In my aforesaid application it is explained how by 85 operations of the clutch *f'* a dwell is effected in each cycle of movement of the lever, and hence of the main slide and the parts it carries, in order to afford proper time for the filling; but that is not material 90 here.

In the main slide is arranged an organization of parts as follows: *q* is a slide (termed herein the "compensating slide") 95 penetrating the main slide and normally supported by its flange *r* resting on the top of the main slide, and carrying at its lower end the filling and sealing head *s* (to be described later in detail), screwed thereon. Slide *q* is adapted to yield upwardly in the 100 main slide for compensating for varying heights of bottles assumed to be of the same height and thereupon be positively held by, for downward movement with, the main slide thus: Said slide has a toothed surface 105 *t* exposed at the front by opening *p'* in the

main slide front plate p and adapted to be engaged by spring-pressed pawls u pivoted in the ears p^2 when said pawls, in the descent of the main slide, run off the surfaces 5 v of the plates l' . Telescoped over the upper end of the compensating slide and secured thereon by the nut w is a tubular upright extension x which has a roller-bearing support y against the back of the (fixed) 10 hopper n and a cap z screwed on its upper end, its lower end being provided with front-to-rear slots 2. In the compensating slide and projecting up through its extension x is a hollow plunger comprising lower 15 and upper tubes 3 and 4 connected by the union 5 which has a nipple 6, for attachment thereto of the filling-liquid supply tube 7, and a hardened shoulder 8 respectively projecting through the front and rear 20 slots 2, said plunger also comprising the tubular extension 9 screwed into the tube 3 and containing a spiral 9' for imparting a swirling action to the filling liquid. A spiral spring 10, housed in the extension x , 25 is interposed between union 5 and cap z , normally holding down the plunger to a limit afforded by contact of the union with the upper end of slide q . A nut 11 screwed on the upper end of tube 4 affords a ful- 30 crum for a lever 12.

Plunger extension 9 affords a valve seat 13 at its upper end. This valve seat is normally closed by the valve 14 at the lower end of a long spindle 15 which penetrates the plunger 3-4 and is held depressed by a spring 16 set in the upper end of the spindle and held under compression by an arm 17 that projects from a rigid part of the extension x of the compensating slide. On the upper 35 end of the spindle is screwed a collar 18 by means of which, when the plunger 3-4 is stopped in the downward movement of the main and compensating slides by contact with the bottle head, lever 12 acts to produce 40 a differential movement of the spindle relatively to the plunger, raising the spindle and hence the valve 14 from its seat, said lever being tilted by a dog 19 (pivoted in and bearing upwardly against arm 17), in moving downward with the compensating slide, 45 pressing downwardly on the free or outer end of said lever.

The filling and sealing head s has a mouthpiece 21 provided with radially movable inwardly spring-pressed beveled guides 22, for cushioning the impact of the bottle mouth therewith, and supporting an elastic gasket 23, a ring 24 resting on the gasket and having an internal closure-supporting ledge 25 55 and an annular closure affixing appliance 26, the parts 23, 24 and 26 being housed in the head s and penetrated by the tubular plunger extension 9. The head has at the front a closure inlet 27, which also penetrates the 60 ring 24. The mouthpiece is supported by 65

suitable means unnecessary of more detailed description herein than to say that the same includes two rods 28 coupled at their lower ends to the mouthpiece and normally drawn upwardly by suitable means stepped on the head s , the construction being such that the mouthpiece supporting means normally causes the mouthpiece to hold the gasket compressed and is made to release the gasket after, in each filling operation, its sealing function is no longer needed, all as explained in my aforesaid application. 70

When the main slide descends, the plunger 3-4 on impact with the bottle head, together with the compensating slide supported on the plunger through the medium of its extension x and spring 10, will stop until, compensation being attained, pawls u lock the compensating slide to the main slide 80 and cause the former to descend, which (as will appear) involves a comparatively slight movement, followed by the dwell which has been hereinbefore alluded to; such movement, since the plunger is prevented by the bottle from partaking thereof (spring 10 90 being in consequence somewhat compressed) involves raising of valve spindle 15 and the consequent opening of the valve 14 for the flow of the filling liquid to the bottle, caused by dog 19 tilting lever 12 as it descends. The 95 dwell occurs, as explained in my said application, while the lever stands thus tilted, and upon the bottle being filled the valve must be closed and plunger 3-4 raised enough to elevate the plunger extension 9 clear of the 100 bottle head and above closure inlet 27 to admit the closure to the ledge 25 of ring 24. To accomplish these functions there is provided the following mechanism:

A bell-crank lever 29 is fulcrumed in a 105 fixed part of the extension x of the compensating slide and has on one arm a roller 30 and pivoted to the other a depending hook 31 whose lower (hooked) end is normally pressed against union 5 of plunger 3-4 by a spring 32 (Fig. 5); the hook has a depending shoe 33 adapted to coact with the upper end of a certain rod 34 forming a 110 part of the means which, as aforesaid, causes the mouthpiece supporting means to relax its pressure on the gasket 23. When, the compensating being effected, the compensating slide makes the slight downward movement mentioned relatively to the plunger 3-4, hook 31 is caused by its spring to latch under 115 shoulder 8 on the plunger; then, immediately after the dwell, by means to be described pressure is effected on roller 30, whereby lever 29, in tilting, through the medium of the hook raises the plunger, lever 12 being caused to clear the dog 19, allowing 120 the valve to close, and the plunger being carried up until its extension 9 is clear of the bottle head and above the closure inlet 27. 125

The closure supply chute is stationary and has at its discharge end a spring-pressed retaining pawl 36 which supports the whole line of closures in the chute except when it is uplifted by the head *s* as the same comes to its highest elevation, allowing a closure to enter the inlet 27 and rest therein against the plunger extension 9. When the main slide and the other parts carried thereby descend and come to a dwell and then the plunger is lifted to clear the closure inlet the waiting closure is forced onto the closure seat 25 thus: An arc-shaped gate 37 is fulcrumed in the sealing head *s* between two ears 38 thereon so as to move in a horizontal plane, and it houses a spring-pressed tongue or pusher 39 adapted to register with and enter the closure inlet when the gate is swung against the front face of the head. The fulcrum of the gate is a shaft 40 journaled in the ears 38 and a bearing 42 on the right hand ear *p*² of the main slide, the shaft being splined to the gate (Fig. 9), so as to allow relative movement vertically, and caused to reciprocate with the main slide by the collar 43 and a crank-sleeve 44 thereon abutting oppositely against the bearing 42, the former being pinned to the shaft and the latter yieldingly held against turning relatively thereto by the torsion spring 45 fastened at one end to the crank-sleeve and at the other to a suitable head-piece 46 keyed to the shaft. The arm or crank portion of the crank-sleeve is equipped with a roller 47 engaged in a cam-slot 48 in the housing *m*, and it has an upstanding projection 49 which normally abuts against a lug 50 on a sleeve 51 pinned to the shaft (see Figs. 7, 10 and 11). When the main slide is up the gate is open (Fig. 3), the closure inlet 27 being then opposed by the lower end of the chute 35; when it has descended to the position for dwell the roller 47 is at the upper end of the straight part of the cam-slot forming its lower end. In the latter position the gate is held by the torsional pressure of spring 45 in sealing relation to the side of head *s*; its pusher 39 is held retracted or sheathed in the gate by the waiting closure housed in the mouth of the closure inlet and bearing laterally against the plunger-extension 9. When, at the end of the dwell, the plunger-extension is elevated, the closure is thrust to its seat on ledge 25 by the spring-pressed pusher. When, after further downward movement succeeding the dwell, the main slide again rises, the cam-slot causes the gate to be thrown open, clear of the lower end of the chute. Spring 45 eases the action of the cam-slot to close the gate, as well as exerts a yielding pressure on the gate when closed, while the positive engagement of the projection 49 against lug 50 occurring when the roller 47 travels up the

cam-slot causes the opening movement of the gate to be quick where it might be so sluggish as to involve interference of the gate with the chute if the turning movement were imparted to the shaft through the spring.

The closure supply hopper *n* has its bottom wall sloping toward the front wall 53, which is a disk journaled on the stud 54 and having beveled and peripheral gear teeth; on the back of this disk is a concentric groove 55 formed gradually deeper toward its outer edge. There is a space 56 somewhat greater than the thickness of a closure between the marginal portion of the disk and the front surface 57 of the hopper, which portion is flanked by a flange 58 that extends concentric with the disk and close enough thereto to retain the closures in said space except at the bottom, where an opening 59 (Fig. 3) is left to admit the closures to the chute; surface 57 is plane except for a rounded rib 60 registering with groove 55. The disk has two sets of apertures 61 in alternating radii, one set being in a circle of less diameter than, and the other registering with, the groove. Secured by suitable means to the outer face of the disk are yielding agitators 62 (in the form of rebent lengths of wire) which project through the apertures. An incased suitably journaled rotary agitator 63 (herein taking the form of a toothed wheel meshing with the peripheral teeth of the disk 53) is arranged with its periphery projecting slightly into the chute and also into the space 56. Through the medium of the shaft 64 journaled in the hopper and equipped with a driving pulley 65 and with a bevel pinion 66 meshing with the beveled teeth of the disk, the latter and the agitator 63 are rotated in the direction of the arrow seen in Fig. 3. A mass of closures placed indiscriminately in the hopper will be tumbled by the relatively inner set of agitators 62, thus promoting their being faced properly to pass the coating rib and groove 55 (see my Patent No. 1,042,068); any which would otherwise remain caught in the groove are dislodged by the relatively outer set of agitators; and, finally, any that might tend to clog the outlet (entrance to the chute) are disturbed by the agitator 63, which further prevents congestion at the outlet, due to the chute filling up with the closures, by directing the surplus to the right and so back into the mass in the hopper along the upwardly curving runway which the right-hand part of the flange 58 forms. The pulley 65 is driven by a belt 67 extending around a pulley 68 on shaft *g*. In suitable bearings in pedestal *a* and housing *b* is journaled a vertical shaft 69 provided at its upper end with a vertically elongated arm 70 for actuating the lever 29

and at its lower end with a crank 71 having a roller 72 engaged in the groove of the barrel cam 73 on shaft *g*.

Operation: In the position of the parts as shown in Fig. 5, which may be taken as the inception of a cycle, the compensating slide is supported by its flange *r* on the top of the main slide, which is fully elevated; the plunger 3—4 is fully depressed in the compensating slide, as also the valve 14, which thus prevents the liquid flow; hook 31 is held bearing against the back of shoulder 8 by spring 32, lever 29 in turn bearing against the arm 70 of lever 69; the closure check 36 is retracted by the head *s*, so that the lowermost closure in the line rests against the side of the plunger-extension 9; and the gate 37 is in the open position (Fig. 3). When the main slide descends there occur the following operations, already indicated: Arresting of the downward movement with the main slide of the compensating slide as soon as the plunger-extension comes to rest on the bottle, thus to effect compensation, followed by pawls *u* locking the compensating slide to the main slide and the compensating slide then moving downward relatively to the plunger, whose spring 10 is put under compression, such movement of the compensating slide with the main slide being just enough to enter the bottle head into the contracted gasket without clearing the plunger-extension 9 from the gasket; at this point, in the construction herein illustrated, the dwell hereinbefore noted, occurs. Meanwhile the closure check has resumed checking position and the downward movement of the main slide has resulted in the gate 37 closing so that its pusher presses the waiting closure in inlet 27 against the plunger-extension 9. The slight downward movement of the compensating slide with the main slide effected opening of the valve 14 and resulted in the hook 31 latching under the shoulder 8. The filling being completed and the dwell ceasing, the main slide continues downward, positively carrying down with it the compensating slide, still locked thereto by the pawls *u*, the result of which movement is ultimately to perform the closure-affixing operation. But the plunger 3—4 must be raised to shut off the liquid flow and elevate plunger-extension 9 above the inlet and also clear of the bottle head to enable the pusher to introduce the waiting closure to the ledge 25, over the bottle head, and this is accomplished by cam 73 imparting a quick movement to lever 69 which rocks lever 29 on its fulcrum. The downward movement is now completed, resulting first in the plunger coming to bear on the closure, now superimposed on the bottle head, and next in the closure flange (the closure for which the machine illustrated is especially adapted being of the so-called "Crown" type—Fig. 8) be-

ing bent by the affixing appliance into locking engagement with the usual shoulder on the bottle, the plunger (its spring yielding) and bottle holding the cork-lined closure under compression until the affixing is finally effected; in this movement roller 30 of lever 29 runs down the vertical face of arm 70, the extension *x* of the compensating slide being at that time supported by its roller *y* bearing against hopper *n*. At the end of the downward stroke, after the plunger again is opposed by the bottle, shoe 33 of hook 31 wipes against the rounded top of rod 34 and thus retracts the hook clear of shoulder 8.

On the return or upward stroke, the plunger first comes to its normal position in the compensating slide, ejecting the bottle head from the head *s*, and then the compensating slide resumes its normal position in the main slide (its flange *r* resting on the latter). The hook 31 clears shoulder 8 because it has been retracted as above stated and lever 69 has been retracted by its cam; and as lever 19 rises with the compensating slide it is simply wiped idly aside by lever 12. In the upstroke the gate is opened by the cam-slot 48 and thus made to clear the lower end of the chute, and at the end of such upstroke the closure check is retracted by head 3 so as to admit another closure to inlet 27.

The term "coacting means to exert closure-affixing pressure" hereinafter used in the claims will be understood as referring in the present disclosure, on the one hand, to the structure which supports the bottles and includes fixed frame parts of the machine and, on the other, to the structure movable up and down and at the front of the housing *b* and carrying the sealing head.

Having thus fully described my invention, what I claim and desire to secure by Letters Patent is:

1. In combination, coacting means to exert closure-affixing pressure on a container and its closure interposed between them, one of said means including a closure-receiving head having a closure-receiving throat and a closure-inlet leading laterally to said throat, means to deliver a closure into the inlet, said head being movable, during the closure-affixing thrust of said coacting means, away from the closure delivery means and with the one of the coacting means which includes such head, and means to press the delivered closure into the throat upon said movement.

2. In combination, coacting means to exert closure-affixing pressure on a container and its closure interposed between them, one of said means including a closure-receiving head having a closure-receiving throat and a closure-inlet leading laterally to said throat, means to deliver a closure into the inlet, said head being movable, during the

working thrust of said coacting means, away from the closure delivery means and with the one of the coacting means which includes such head, an inlet obstructing device in the 5 throat, means to press the delivered closure against said device upon such movement, and means thereupon to withdraw said device clear of the inlet to admit the closure to the throat.

10 3. In combination, coacting means, movable one toward and from the other, for exerting closure-affixing pressure on a container and its closure interposed between them, one of said means including a closure- 15 receiving head having a closure inlet, a closure-affixing means in the head, and a closure introducing appliance movable on an axis substantially parallel with the pressure thrust line of said means and ar- 20 ranged, in one and having a movement-effecting engagement with the other of them.

4. In combination, coacting means, movable one toward and from the other, for exerting closure-affixing pressure on a con- 25 tainer and its closure interposed between them, one of said means including a closure-receiving head having a closure-inlet, a closure-affixing means in the head, a back and forth movable closure introducing ap- 30 pliance movable in one of said coacting means and a spring normally urging said

appliance in one direction, said appliance being engageable by the other of said coacting means and thereby adapted to be moved in the opposite direction. 35

5. In combination, coacting means, movable one toward and from the other, for exerting closure-affixing pressure on a container and its closure interposed between them, one of said means including a closure- 40 receiving head having a closure-inlet, a closure-affixing means in the head, and a closure introducing appliance movable on an axis substantially parallel with the pressure thrust line of said means and arranged 45 in one and having a movement-effecting engagement with the other of them, said appliance having an elastic closure pusher.

6. In combination, coacting means, movable one toward and from the other, for exerting closure-affixing pressure on a container and its closure interposed between them, one of said means including a closure- 50 receiving head having a closure inlet, a closure-affixing means in the head, and a 55 closure introducing appliance movable on an axis substantially parallel with the pressure thrust line of said means and arranged in one of them, the other of said means having a cam engaging said appliance. 60

In testimony whereof I affix my signature.
AMOS CALLESON.
